UNITED STATES PATENT OFFICE.

HYMAN GELLMAN, OF NEW YORK, N. Y.

SAFETY-LOCK FOR FOOT-LEVERS.

1,384,251.

Specification of Letters Patent. Patented July 12, 1921.

Application filed May 7, 1920. Serial No. 379,487.

To all whom it may concern:

Be it known that I, HYMAN GELLMAN, a citizen of the United States, and resident of New York, in the county and State of New York, have invented certain new and useful Improvements in Safety-Locks for Foot-Levers, of which the following is a full, clear, and exact specification.

This invention relates to safety devices for preventing the premature or accidental operation of a foot lever such as is used for actuating presses of various kinds, and has

for its object to provide a simple form of device for supporting the foot of the operator and movable by him from below the lever when it is desired to depress the same, said safety device being automatically returnable to locking position when pressure is removed therefrom.

20 The actuation of punching and other kinds of presses at the wrong time has caused many accidents, such as the loss of fingers and injury to the hands of the operators.

It is the aim of the present invention to provide a device for normally supporting the foot lever for actuating such presses or the like, so that said lever cannot be actuated or depressed, until the device is withdrawn by drawing the foot back. Means is also provided for automatically returning the safety device to normal position for again locking the lever against actuation as soon as pressure is removed from said device and the lever.

35 The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

45 Figure 1 is a longitudinal vertical section of a safety device constructed substantially in accordance with this invention, showing the same in normal locking position below the foot lever of any suitable machine, the withdrawn position of the device being indicated in dotted lines.

50 Fig. 2 is a plan view of the safety device.

Fig. 3 is an end view of the same looking

at the right hand end thereof as shown in Fig. 2, and

55

Fig. 4 is a section through the carriage in line with one of the wheel carrying axles.

In Fig. 1, a foot lever of a press or other machine (not shown) is indicated at 1, the same being pivoted at 2 and having the foot piece 3 at its free end while its other end is connected by a rod 4 to the mechanism to be operated. The safety device comprises a floor plate 5 having rails 10 on its upper surface, and a reciprocating carriage 11 mounted on wheels 12 and normally adapted to support the foot piece 3 of the lever as shown in solid lines in Fig. 1. Said carriage has a step or abutment 20 near its front end over which the end of the foot piece 3 of the lever is adapted to pass for allowing said lever to be actuated, as indicated in dotted lines in Fig. 1, when the carriage is drawn back.

65

The carriage is yieldingly held in locking 75 position by springs 14 and 17. Two of the springs 14 are connected to the front end of the carriage at 15 and to a front flange 6 on the floor plate 5 at 16, while the spring 17 is connected at one end to a pin 18 on the 80 floor plate below the carriage and to another pin 19 on the rear end of the carriage at its other end. The number and positions of these springs may, however, be changed, if desired.

85

The forward movement of the carriage is preferably limited by a transverse rib or flange 7 on the floor plate 5, and to prevent said carriage from leaving the rails 10 lateral flanges 8 having overhanging ledges 90 9 are provided at the sides of the floor plate extending rearward from said transverse flange or rib 7. The overhanging ledges 9 extend over the lateral edges of the carriage 11, as shown in Figs. 2 and 3. The wheels 95 12 may be suitably mounted on axles 13 extending across the carriage near the front and rear ends thereof.

95

At the rear end of the carriage there is provided a heel piece of flange 21 adapted 100 to conform generally to the rear portion and sides of the heel of a shoe, so that when the foot of the operator is placed on the carriage, as indicated in dotted lines in Fig. 1, the heel of the shoe may abut against said heel piece and the foot be retained in op-

erative position on the carriage thereby. The heel piece also permits the carriage to be moved rearwardly when the foot of the operator is drawn backward while in operative position thereon.

As already explained, the normal position of the carriage is that shown in solid lines in Fig. 1 where it is in its farthest front position and supports the foot piece 3 of the lever 1 above the step 20. Now, when it is desired to depress the foot lever for operating the mechanism which it controls, it is necessary for the operator to draw back the carriage with his foot against the tension of the springs 14 and 17 until the step 20 passes beyond the free end of said lever, whereupon the latter may be depressed by the ball of the foot. Just as soon as the pressure on the foot lever is removed and it has risen above the level of the floor of the carriage, the rearward pressure on the carriage may also be removed and the springs 14 and 17 will return said carriage to its forward locking position again. Inasmuch as the foot lever cannot be operated until the carriage has been moved rearwardly by the operator's foot, the accidental operation of said lever is not likely.

Having thus described my invention, what I claim as new and desire to secure by Letters Patent of the United States is:

1. The combination with a foot lever, of a carriage to normally support said lever and lock the same against operation, and foot-holding means on said carriage whereby the latter may be withdrawn from below the lever by the foot of the operator and the lever actuated by the same foot while on the carriage and holding the same in withdrawn position.

2. The combination with a foot lever, of a carriage to normally support said lever and lock the same against operation, foot engaging means on said carriage whereby the latter may be withdrawn from below the lever by the foot of the operator and the lever actuated by the same foot while on the carriage and holding the same in withdrawn position, and means for automatically returning the carriage to normal position below the lever when the pressure of the foot on the lever and carriage is removed.

3. The combination with a foot lever, of a floor plate arranged below the same, a carriage mounted to be reciprocated on said floor plate, means for yieldingly holding

said carriage in position to support the lever and lock the same against operation, and foot engaging means on said carriage whereby the latter may be withdrawn from below the lever by the foot of the operator and the lever actuated by the same foot while on the carriage and holding the same in withdrawn position.

4. The combination with a foot lever, of a floor plate arranged below the same, rails on said plate, a carriage mounted on wheels engaging said rails, means for yieldingly holding said carriage in position to support the lever and lock the same against operation, means on the foot plate to limit the movement of the carriage to locking position, and means on the carriage for engaging the foot of the operator whereby said carriage may be withdrawn from below the lever by said foot and the lever actuated thereby while the carriage is held in withdrawn position.

5. The combination with a foot lever, of a floor plate arranged below the same, a carriage mounted to be reciprocated on said plate, means for retaining said carriage in operative position on the plate, means for yieldingly holding said carriage in position to support the lever and lock the same against operation, and foot engaging means on the carriage whereby the latter may be withdrawn from below the lever by the foot of the operator and said lever actuated by the same foot while on the carriage and holding the same in withdrawn position.

6. The combination with a foot lever, of a floor plate arranged below the same, a carriage mounted to be reciprocated on said plate, lateral flanges on the plate with ledges overhanging the sides of the carriage for retaining the latter in operative position on the plate, and foot engaging means on said carriage whereby the latter may be moved to release the lever by the foot of the operator.

7. The combination with a foot lever, of a floor plate arranged below the same, a carriage mounted to be reciprocated on said plate from a position below the lever to a position for releasing said lever, and springs connected to the plate and carriage for automatically returning the carriage to lever locking position.

In testimony whereof I have signed my name to this specification.

HYMAN GELLMAN.
